UNITED STATES PATENT OFFICE.

FREDERICK S. LOWRY, DECEASED, LATE OF ROSEVILLE, OHIO, BY MILDRED L. HART,
FORMERLY MILDRED LOWRY, ADMINISTRATRIX, OF ROSEVILLE, OHIO.

MOLD FOR CERAMIC PRODUCTS.

1,314,821.

Specification of Letters Patent. Patented Sept. 2, 1919.

Application filed March 1, 1919. Serial No. 280,086.

To all whom it may concern:

Be it known that I, MILDRED L. HART, a citizen of the United States, residing at Roseville, in the county of Perry and State 5 of Ohio, am the administratrix of the last will and testament of FREDERICK S. LOWRY, deceased, formerly of Roseville, Perry county, Ohio, who has invented new and useful Improvements in Molds for Ceramic 10 Products, of which the following is a specification.

This invention relates broadly to molds, and has particular reference to an improved mold applicable for use in effecting the 15 formation of clay products, particularly cooking utensils.

The object of the invention is to provide a mold of this character with improved means for effecting the forming of offset 20 handle receiving projections upon such utensils or receptacles, and is of such construction as to permit the projections to be formed at positions below the rims of the utensils, the mold also carrying novel means 25 which assist in the formation of the projections, and which permit the latter to be readily removed from the mold in a finished condition and without the liability of damage or breakage thereto.

With these and other objects in view, as 30 will appear as the description proceeds, the invention accordingly consists in the novel features of construction, combinations of elements and arrangement of parts, herein- 35 after more fully described and having the scope thereof defined in the appended claims.

In the accompanying drawing, forming a 40 part of this specification, and in which similar characters of reference denote like and corresponding parts:

Figure 1 is a top plan view of the mold comprising the present invention.

Fig. 2 is a vertical sectional view thereof 45 taken along the line 2—2 of Fig. 1.

Fig. 3 is a fragmentary perspective view of the mold disclosing more particularly the construction of the ear forming pocket and its coöperative plate receiving recess.

Fig. 4 is a detailed perspective view of 50 the pocket inclosing plate.

Fig. 5 is a detail handle to be inserted in the ears of the receptacle.

Referring more particularly to the de- 55 tails of the invention, use is made of a mold

1, which is preferably of bowl shape configuration and is formed from plaster or other similar material. It will of course be understood that the materials forming a ceramic receptacle are placed into the hollow interior 2 of the mold, and are then pressed against the sides thereof to effect their final shapes, and the mold is preferably placed upon a revolving table to facilitate this operation.

Heretofore, considerable difficulty has been occasioned in forming the offset handle receiving projection or ears 3 upon the sides of the receptacles 4, and to cause such projections to be positioned below the rim of the receptacle. To accomplish this, it has been the common practice to provide the rims of the molds with ear forming pockets, which were in open communication with the upper surface of the mold rim, in order that after 75 a receptacle had been formed no difficulty would be encountered in effecting its removal from a mold. It is obvious that this construction left the upper portions of the projections 3 flush with the rims of their 80 receptacles, so that in order to lower or reduce the height of the projections it has been necessary to cut away the upper part of said projections, so that the latter would occupy a plane beneath that of the receptacle rim. 85 Through the provision of the present invention, a structure has been provided whereby this cutting away of the projections 3 is eliminated, facility in effecting the removal of the completed receptacle from the 90 mold is afforded, and a pleasing and attractive appearance imparted to the receptacle at points adjacent to the ear formation. This latter feature is not to be found in receptacles which have the projections 3 reduced in size by cutting operation, as the latter always have a tendency to mar or score the receptacle so that an unattractive appearance is presented.

To this end, the interior of the mold is 100 provided at points diametrically opposed and adjacent to its rim 5 with a pair of ear forming pockets 6, which are provided with curvilinear vertical walls 7 and horizontal, substantially flat bottom walls 8, which define the approximate formation of the ears or projections 3. It will be noted that these pockets are in open communication with the interior of the mold, and therefore the plastic material employed in forming the recep- 105 110

tacles 4 will be pressed into said pockets to form the projections 3 during the process of forming the receptacles. In order to locate the ears 3 on a plane beneath the rim 9 of the receptacle 4, use is made of a pair of removable wedge plates 10, which are disposed to occupy similarly formed recesses 11 located in the rim 5 of the mold, and which are located in open communication as 10 it were with the pockets 6. Said recesses are formed to include vertical walls 12, which are positioned immediately adjacent to the interior wall of the mold 1, and are disposed to terminate in outwardly diverging walls 13. The latter are also downwardly beveled so that the distance between their lower surfaces is appreciably greater than that between their upper surfaces or edges. The walls 13 terminate in radially disposed walls 20 14 which are spaced so that the recesses 11 will open into the exterior of the mold. The wedge plates 10 are constructed to interfit within the recesses 11, and are therefore formed to provide vertical walls 15 corresponding to the recess walls 12, and also with downwardly beveled walls 16 corresponding to and adapted to interfit with the walls 13 of said recesses. A vertical wall 17 connects the beveled walls 16 and the recess walls 14, and therefore terminates short of the space between said walls 14. This provides a finger space between the latter walls to facilitate the removal of an associated wedge plate.

35 From the foregoing description, it will be seen that when a receptacle is being formed within the mold 1, the plastic material comprising the same will also be forced into the pocket 6 and will be prevented from rising 40 to a position flush with its rim by means of the plates 10. The latter, in turn, will be locked within the recesses 11, by virtue of the fact that in forming the receptacle the thrust upon said plates is in a horizontal 45 and radial direction. This action causes the walls 16 of the plates to be held in close contact with the beveled walls 13 of the recesses, thus preventing undue vertical movement on part of said plates, also on account of the 50 outward divergence of the walls 13, outward radial movement on part of the plates is precluded. Therefore, a structure is provided which will firmly retain the plates 10 in proper position during the normal process 55 of receptacle formation, and since pressure upon the plate always tends to force the latter outwardly or upwardly, uncontrolled movement thereof is avoided. To provide bail receiving openings in the ears 3 of the 60 receptacles, the plates 10 are provided with one or more openings 18, by means of which a wire may be inserted therethrough so as to penetrate the ears 3, thus permitting a bail or handle 19 to be readily associated 65 therewith after the receptacle has been dried.

It will be further noted that when the plates 10 are locked within the recesses 11, their rear curved faces 20 will exactly coincide or register with the curvature of the wall forming the interior of the mold. This eliminates 70 the presence of objectionable marks upon the completed receptacle. After the receptacle 4 has been completely formed, the same is permitted to dry for a short time within the mold, and this causes a slight reduction 75 in the general proportions of the receptacle, so that its rim will be slightly spaced from the walls 20 of the plates. This enables the plates to be moved inwardly to such extent that its walls 16 will clear the co-operating 80 walls 13 of the recesses 11, so that the plates may be removed from said recesses by lifting the same vertically therefrom. When the plates are thus removed, the pockets 6 are in open communication with the mold 85 rim, so that the receptacle with its associated ear projections may be removed from said mold without the slightest hindrance. It will be thus manifest that a mold is provided 90 wherein provision is made for forming the ears 3 on a plane beneath that of the receptacle rim, one wherein the necessity of slicing or paring the ears is eliminated, and one wherein facility is to be had in effecting the removal of a completed receptacle from the 95 mold. Another important feature of the invention resides in the beveled walls 13 and 16 of the recesses and plates respectively, which serve to lock the plates in wedged relation with the mold body during the normal 100 process of forming the receptacle 4.

What is claimed is:

1. In a mold for producing ceramic vessels, comprising a substantially bowl shaped body having pockets formed therein and in open communication with the interior of said body to permit of the formation of offset projections upon the sides of vessels formed in said mold, and to locate such projections below the rims of their vessels, and removable means carried by said mold and forming the tops of said pockets.

2. In a mold for forming handle ears upon ceramic vessels, comprising an open top receptacle having a pocket formed on the interior face thereof at a position contiguous to and below the rim of the mold, said rim having a recess formed therein in communication with said pocket, and a separable pocket inclosing element shaped to 115 occupy said recesses and capable of being removed therefrom to permit of the removal of a vessel from the mold.

3. In a mold for forming handle receiving projections upon ceramic vessels, comprising a bowl shaped receptacle having pockets formed on the inside thereof and opening laterally into the hollow interior of the mold, said pockets being spaced from the rim of said mold, and removable means situ-

ated between the upper edges of said pocket and the rim of said mold and serving to define the upper surfaces of projections formed in said pockets.

5. In a mold of the class described comprising a hollow bowl shaped body, the interior of said body being provided adjacent to its rim with a pair of ear forming pockets, the rim of said mold adjacent to said pockets being formed with wedge shaped recesses, and a plurality of wedge members operable to interfit within said recesses and serving to space said pockets from the rim of said mold.

10. 5. In a mold of the class described, the combination with the inner wall thereof,

said wall being provided adjacent to the rim of the mold with a pair of diametrically opposed pockets, said rim being provided adjacent to said pockets with a pair of wedge shaped recesses, the diverging walls of said recesses being beveled, of means for inclosing said pockets comprising a pair of wedge shaped plate members, disposed to occupy said recesses and serving to space said pockets from said rim, and beveled walls carried by said members, and interfitting with said recess walls.

In testimony whereof I affix my signature.

FREDERICK S. LOWRY,
By MILDRED LOWRY HART,
Administratrix.
